UNITED STATES PATENT OFFICE.

VERNOR T. BARKLEY, OF PITTSBURGH, PENNSYLVANIA.

HOISTING CAGE.

Application filed September 15, 1920. Serial No. 410,530.

To all whom it may concern:

Be it known that I, VERNOR T. BARKLEY, a citizen of the United States, and resident of Pittsburgh, in the county of Allegheny and State of Pennsylvania, have invented a new and useful Improvement in Hoisting Cages; and I do hereby declare the following to be a full, clear, and exact description thereof.

10 My invention relates to hoisting cages for use in shaft coal mines and for similar purposes.

The object of my invention is to provide a practical and economical apparatus for 15 hoisting coal from shaft mines that are equipped with solid cars having no seams or end gates, and to overcome the objectionable features of the overturning skips and guide-controlled tilting cages now employed 20 for hoisting coal from shaft mines.

The method heretofore employed for hoisting coal from a shaft mine equipped with solid cars consists in dumping the coal from the cars at the shaft bottom, commonly by 25 means of power-driven apparatus, into a hopper from which the coal passes into skips or buckets and is hoisted. This makes it necessary to excavate a pit below the coal seam, and this pit, which is about sixty feet 30 deep, naturally becomes a sump or drain, since it is at the lowest part of the mine, and a pumping station must therefore be provided. This method is not only expensive but has practical objections such as the 35 breakage of soft lump coal.

My present invention aims to eliminate the dumping of the coal at the bottom of the shaft; to deliver the coal from the cars directly to the receiving hopper or chute in 40 the tipple, with little or no breakage, even if the hoist should over-wind; to increase the hoisting speed by doing away with the excessive distance of slow hoisting that is now necessary to turn the present skips and 45 cages to dumping position and the similar loss of time in returning the skip or cage to the shaft bottom, and to provide a cage in which the entire weight is always effective to balance the other cage in the shaft. 50 With these and other objects in view my invention provides, in combination, a hoisting cage and a gravity rotary dump mount-

ed in the cage on frictionless bearings, the cage and dump being of simple and rugged construction, complete and positively controlled. Two cages are employed together, one rising with a loaded car while the other is descending with an empty car and each cage operate to hoist a loaded car carried on the dump and to rotate the dump by gravity 60 while the car is being hoisted and before the cage that carries the empty car reaches the bottom of the shaft, so that before the cages reach the end of their travel they are both empty and in equilibrium. While the dump 65 is rotating with the loaded car, a chute which is also carried by the cage is lowered by means of suitable guides into proper position to receive the load from the car and deliver it to the receiving chute in the tipple, 70 and the chute is again raised by the guides while the cage is descending the shaft. As the cage descends in the shaft, the dump is rotated by gravity in the reverse direction 75 to bring the empty car to an upright position.

In the accompanying drawings, Fig. 1 is a side elevational view of a hoisting cage constructed in accordance with my invention for handling 3-ton coal cars, showing the cage as it approaches the top of its travel; Fig. 2 is a side elevational view similar to Fig. 1, showing the cage in the dumping position; Fig. 3 is an end view of the same structure; Fig. 4 is a plan view with parts in section on the line 4—4, Fig. 1; Fig. 5 is a fragmentary elevational view showing the horn-releasing trigger mechanism at the bottom of the shaft; and Fig. 6 is an enlarged elevational view of one of the rear horns and its operating mechanism.

As shown in the drawings, the cage includes a rectangular supporting frame composed of side plates 1 connected by cross bars 2 and carrying vertical angle bars 3 which form guides for engaging the usual vertical timbers 4 of the mine. The lower ends of the guides 3 are connected by a channel plate 5 and the top of the cage is also provided with the usual hoisting rigging and safety attachments, the details of which form no part of my invention.

The side plates 1 carry bearings 6 in which is supported a fixed shaft 7 that is

somewhat to the left of the center line of the guides 3 as shown in Figs. 1 and 2, and carries a rotatable car dump 8 resting upon bearings 9 mounted on the shaft 7. The dump 8 consists of a suitable frame-work supported on the bearings 9 and carries a pair of tracks composed of angle bars 10 secured to the upper edges of the side plates 11 of the dump. A pair of front horns 12, and 10 a pair of rear horns 13 are also carried by the dump, these horns being adapted to grip and hold the wheels of a car 14. The dump 8 swings between the fixed side plates 2 on which are secured the guides 3. The 15 center of gravity of the dump 8 is so disposed that the dump is slightly unbalanced to the left of the supporting shaft 6 while carrying an empty car, so that the cross bar 2 at the left of Fig. 1 holds the car 20 support level at this time. When the dump carries a loaded car, the center of gravity of the dump and all rotating parts is on the right of the shaft 6, so that the dump tends to rotate by gravity to the right. 25 The side plates 1 form a chamber which communicates with a downwardly extending fixed chute 19, the lower end of which opens into a movable tapered chute 20 that is pivotally secured at one end to a shaft 21 which 30 extends between the guides 3 and is received in bearings 22 on the channel plate 5. The under side of the chute 20 carries bearings 23 in which is mounted a shaft 24 to the ends of which are rigidly secured two castings 25, each of which has a short extension 26 received between the rounded ends of two pins 29 which extend through openings in a bracket 28 and carry two compression springs 27, washers 30 and nuts 31. 35 The chute 20, being tapered, requires a relatively small receiving hopper. 40 The upper ends of the castings 25 are connected by means of a horizontal shaft 32, the ends of which carry rollers 33 which 45 are keyed to the shaft 32 and are adapted to enter between fixed guides 34 that are attached to the head frame, and are adjacent to the receiving hopper 35 of the tipple. Since the chute 20 tapers downwardly, the 50 hopper 35 need not be as wide as the cars carried by the dump. Two hooks or latches 36 having lugs 36^a are carried loosely by the horizontal shaft 32, these hooks being adapted to engage pins 37 carried by the guides 55 3, and by brackets 38, thereby holding the movable chute 20 in the position shown in Fig. 1. The shaft 32 also carries loosely two rollers 18 for the purpose of rotating the dump 8 in the manner described below. 60 Two chains 39 are attached to the upper ends of the castings 25 and are connected at their upper ends to bell crank levers 40 which are carried by a shaft 43 underneath the car dump 8 and are connected by means 65 of links 41 to locking pins 42 that are nor-

mally forced outward by means of a spring 44 (Fig. 4) which is secured to a bracket 45 on the dump frame and to a lug 43^a on the shaft 43. It will be evident that when the rollers 33 enter the fixed guides 34 the upward movement of the cage will cause the chute 20 to be rocked downward and will also tighten the chains 39 and thus rock the bell crank levers 40 to withdraw the locking pins 42, leaving the car dump 8 free to rotate in a clockwise direction, Fig. 1, which it then does, being unbalanced to the right of the shaft 7 by the coal in the car, as stated above, until it reaches its dumping position as shown in Fig. 2. A positive stop 2^a is secured to the under side of the side plates 1 for the purpose of limiting the rotation of the dump. 70 75 80 85

The two horns 12 and 13 at each side of the car dump are carried by a shaft 46 that is slidably mounted in bearings 47. A buffer spring 48 surrounds the shaft 46 and is compressed between one of the bearings 47 and a collar 46^a on the shaft 46. The movement of the shaft 46 to the right, as shown in Fig. 1, is limited by means of a collar 50. The loaded car runs upon the car support from the right, Fig. 1, and is stopped by engagement of its front wheels with the front horns 12, the shock being cushioned by the springs 48. The rear horns 13 are opened outward at this time to permit the wheels of the car to pass between them. When the front wheels of the car strike the front horns 12, one of the wheels depresses a trigger 49 which causes the rear horns 13 to close and grip the rear wheels of the car. After the car has been dumped and the cage has descended to the bottom of the shaft, both sets of horns are opened outwardly to release the wheels and permit the empty car to be removed. After the rear wheels of the car pass the front horns, the front horns are closed to receive the front wheels of the next loaded car. These successive movements of the horns will now be described, with reference particularly to Figs. 1, 4, 5, and 6. 90 95 100 105 110

Each of the horns 12 and 13 has a projection 55 which extends downward beyond the shaft 46. Both of the projections 55 from the front horns 12 are connected by means of links 56 to the ends of a lever 57 which rocks on a pin 58 that also carries a lever 59 to which is connected a rod 60 that extends nearly to the end of the car dump 8 and is there connected to a bell crank lever 61 which is secured to a rock shaft 62 and has an outwardly projecting arm 63. As the cage descends in the mine shaft the lever arm 63, as shown in Fig. 1, is in position to engage a stop-member 64 near the bottom of the shaft. The stop-member 64 is carried at the end of a rod 115 120 125 130

65 which is mounted slidably in bearings 66 on any convenient fixed support, a spring 67 being provided to normally force the rod 65 and stop-member 64 into the path of 5 the lever arm 63. The end of the rod 65 opposite to the stop-member 64 is connected by means of a link 68 to a lever 69 on a rock shaft 70, Fig. 5, which carries a trigger 71 that extends above a track 72 so as to 10 be depressed by a car rolling over the track, and the track 72 is in line with the track 10 on the car support 8 when the cage is at the bottom of the shaft.

The rear horns 13 are provided with 15 somewhat different operating connections. Each of these horns, as best shown in Fig. 6, is provided with a recess 75 adjacent to the shaft 46 and a key 76 is carried by the shaft 46 and extends to the recess 75. This 20 arrangement provides a lost-motion connection between the horn 13 and its shaft 46, so that when the horn is rocked outward to release the car wheel and the shaft 46 is afterward rocked back to its starting 25 position the horn 13 can remain in its outward or open position. The downward extending projection 55 from each of the rear horns 13 is attached loosely to a sliding bar 77 which is received in suitable fixed 30 bearings and is surrounded by a spring 78 which tends to close the horn 13 by forcing the bar 77 outward. The bar 77 is provided with a hooked end 79 which is adapted to engage the bent end 80 of a rod 81, best shown in Fig. 4. The rods 81 extend 35 loosely through brackets 82, as shown in Fig. 4, and their front ends are pivotally secured to lugs 84 carried by a rock shaft 83 that also carries the trigger 49 which, as 40 stated above, is adapted to be depressed by one of the front wheels of the loaded car as it rolls upon the dump. A spring 84 rocks the shaft 83 back to its starting position when the trigger 49 is released by the 45 wheel and thus returns the rods 81 into position to lock the bars 77 when the rear horns are again operated.

When the cage descends, the lever 63 engages the stop member 64 and is rotated to 50 the dotted line position shown in Fig. 5, whereby acting through the lever 61 and the rod 60 to rotate the pin 58 against the pull of the spring 73, thus pulling upon the links 56, rocking the shafts 46 and opening the front and rear horns 12 and 13. This 55 releases the wheels of the empty car, and the car is pushed from the cage by the next loaded car which is to be hoisted. The outward rocking movement of the shafts 46 60 brings the hooked ends 79 of the operating bars 77 beyond the ends of the rods 80, which snap in front of the hooks 79 and thus hold the rear horns 13 open. As the empty car rolls from the cage and upon the track 65 72, one of its front wheels depresses the

trigger 71, thereby withdrawing the stop member 64 from the lever 63 and allowing the spring 73 to return the front horns 12 to their upright or operative position. This movement of the front horns is accompanied 70 by a rocking of the shafts 46, which, however, does not cause the rear horns 13 to close, because of the lost-motion connection between the rear horns and the shafts 46. When the loaded car rolls into the cage and 75 its front wheels are stopped by the front horns 12, one of the front wheels, at the same time, depresses the trigger 49, thereby rocking the shaft 83 and thus withdrawing the rods 81 from the bars 77 and permitting the springs 79 to close the rear horns 13 and grip the rear wheels of the car. The horns remain in their closed position while the cage rises and falls and when the cage again reaches the bottom of the shaft the 80 lever 63 again engages the stop-member 64 and the horns are again opened in the manner described above.

In order to brake and control the rotary movement of the car dump 7, I provide a 85 cylinder 85 which is secured to the car dump by means of suitable trunnions 86 received in bearings 87, as shown in Figs. 3 and 4. The piston of the cylinder 85 is connected by means of a connecting rod 88 to a crank pin 89 carried between two crank members 90 that are rigidly secured to the fixed shaft 7. A by-pass pipe 91, controlled by a suitable valve 92, provides communication between the ends of the cylinder on the opposite sides of its piston. A second by-pass may be provided to allow the oil or other fluid contained in the cylinder 85 to return quickly while the car support is being returned to its starting position, and a 95 suitable reservoir should also be provided to replace leakage and keep the cylinder 100 full of oil.

In order to close the space between the side plates 1 at the rear of the car during 110 the dumping operation, I may provide a plate 93 which is vertically movable on a suitable support 94 carried at the upper end of the mine shaft. The plate 93 is adapted to be engaged and lifted by a member 95 carried by the cage and this takes place in time to prevent coal from spilling from the rear of the cage while the car is being dumped.

A counterweight 96 is attached to the under side of the car dump 7, in order to insure that the dump will return to its upright position after the car has been dumped.

The operation of my improved hoisting cage may be best understood by reference to Figs. 1 and 2. Fig. 1 shows the cage at the time when it is rising in the mine shaft or tipple and has almost reached the top of its upward movement. At this time the 125

cage is opposite to the top of the stationary receiving hopper 35. The lugs 36^a now enter between the stationary guides 34 and rock the latches 36 which are loose on the shaft 32, thus unlocking the chute 20. The upward movement of the cage causes the rollers 33 to enter between the guides 34, and these rollers act through the shaft 32 to exert a pull upon the chains 39 which rock the bell crank levers 40 on the shaft 43, thereby withdrawing the locking pins 42 and leaving the car dump 7 free to rotate. The car dump, being unbalanced to the right, Fig. 1, immediately begins to rotate. The dump continues to rotate by gravity until it completes a rotation of about 135° and this takes place while the cage is still moving upward. At the same time, the chute 20 swings downward around its pivot 21 by reason of the engagement between the roller 33 and the fixed guides 34, and its lower end comes over the receiving hopper 35.

The coal falls from the car and down through the fixed chute 19 and the movable chute 20 into the stationary receiving hopper 35, as shown in Fig. 2. It will be observed that the coal never drops through any great distance while being discharged, which prevents the breakage of the coal which has heretofore been a serious disadvantage in hoisting devices for this class of work.

The chute 20 extends beyond the edge of the hopper 35, in order that the chute will always rest on the hopper in case of overwind. Several feet of clearance is always provided between the top of the cage and the bull wheel so that the cage may rise beyond its usual upper position without causing damage, and by this chute arrangement the coal may be delivered at any point between the dumping and the overwind position of the cage without the chute leaving the receiving hopper. The chute will rest upon the hopper at any point between the full line position and the dotted line position A shown on Fig. 2. This permits the head frame to be fully braced without allowing space for the chute in case of overwind.

As the car dump rotates to dump the load, its movement is cushioned and regulated by the fluid-filled braking cylinder 85, the piston of the cylinder being moved by reason of its eccentric connection to the shaft 6 through the stationary crank 90. The speed with which the oil or other fluid passes from one side of the piston to the other, through the pipe 91, is readily controlled by means of the valve 92.

The parts are so proportioned that the chute is lowered to its discharging position before the car rotates far enough to discharge its load, while the car reaches its

limit of rotation or final dumping position, as shown in Fig. 2, at substantially the same time that the cage completes its upward movement. Almost immediately, therefore, the cage is ready to be lowered again. As the cage begins to drop, the lower end of the chute 20, engaging the stationary receiving hopper 35, is raised to bring the rollers 33 down to the curved portion of the guides 34, after which the guides cause the rollers 18 to raise the chute until the latches 36 engage the pins 37 and thus lock the chute in its upper position.

When the cage descends far enough to bring the chute 20 horizontal, the rollers 33 engage the guides 34 and lift the chute from the hopper 35. Just after the rollers 33 enter the guides the loose rollers 18 on the shaft 32 carried by the chute 20, engage the girders of the dump under the rails 10 and begin to rotate the dump back to its upright position, the shock of starting the dump being cushioned by the springs 27. The relation of the parts at this time is shown in dotted lines at B, Fig. 2, and the rollers 18 continue to push the dump around, while the cage is descending in the shaft, until the chute 20 is locked, at which time the center of gravity of the dump has crossed the shaft 7, when the dump comes upright by its own weight. As the dump is thus swinging back to upright position, the locking pins 42 ride on the curved bottom of the chute 19, and are forced out by the spring 44 to lock the dump as soon as the dump is upright. It will be observed that the locking pins move parallel with the rails 10 and lie in the plane of these rails.

When the cage reaches the bottom of the shaft the horns are opened in the manner described above and the empty car is free to be shifted from the cage and replaced by a loaded car, whereupon the horns close automatically, as above described, and the cage is ready to be hoisted.

It will be observed that the time required to dump the load is reduced to a minimum, because the car support is rotating while the cage is rising and finishes its dumping movement practically as soon as the upward movement of the cage is finished.

The cage described above operates to hoist the loaded car, discharge its contents and return the empty car to an upright position without imparting any shock to the hoisting rope, head frame or tipple, or to the cage itself. This renders the cage well adapted for electric and automatic hoisting, which is not the case with the hoisting devices heretofore employed for shaft mines having closed cars. A further advantage is that the coal can be discharged anywhere within the limits of the dumping and full overwind positions of the cage, and the discharge chute will always rest upon the re-

ceiving hopper thus assuming that there will be no dropping and breakage of the coal.

The chute construction is such that the 5 roller 33 cooperates with the stationary guides 34 to lay the chute upon the receiving hopper when the chute reaches its horizontal position, with no shock or slamming effect. Also the chute has a positive lock, 10 since almost the entire weight of the hooks or latches 36 is on the right of the center of moments acting on the chute. The latches can therefore be opened only by positive rotation of the latches.

15 Another advantage of this cage is that its entire weight is always suspended from the hoisting rope, with no support from outside the head frame, and is thus effective at all times to balance the other cage in the same 20 shaft. This eliminates the excessive starting load imposed on the hoist motor in accelerating the cage from the shaft bottom when overturning skips and the present guide-controlled tilting cages are used. The 25 cages are therefore always in balance, whether loaded or empty, and the empty cage at its delivering position loses no part of its weight as a counterbalance to the loaded cage at the bottom of the shaft. 30 The operation of the dump is improved by the buffer springs 48 which absorb the shock while caging cars at the bottom of the shaft, and by the positive governor provided by the piston acting in the fluid-filled 35 cylinder.

The dump carried by the present cage is the first, so far as I am aware, that dispenses with the use of dumping guides and is able to rotate by gravity far enough to 40 dump a closed car, which requires that the dump be rotated through an angle of at least 125 degrees.

It is to be understood that the details of construction which I have herein shown and 45 described may be varied in many respects without departing from my invention and I therefore desire that no limitations be imposed upon my invention except such as are indicated in the appended claims.

50 I claim as my invention:

1. A hoisting cage comprising a rotatably movable car support, a pivotally movable discharge chute, and means operable during the upward movement of the cage for simultaneously rotating the said car support in one direction and for moving the said chute to its operative position by pivotal movement in the opposite direction with respect to the rotary movement of said car support.

2. A hoisting cage comprising a rotatably movable car support, a chute carried by the said cage and pivotally movable thereon from a raised position to a discharging position, a latch for positively locking the said

chute in its raised position and means for releasing the said latch, and means for simultaneously rotating the said car support in one direction and for moving the said chute to its operative position by pivotal movement in the opposite direction with respect to the rotary movement of said car support.

3. A hoisting cage comprising a frame, a car dump carried by said frame, a chute pivotally secured to said frame and movable independently of said dump, means for holding the said chute raised out of its operating position during a part of the upward movement of the cage, and means for lowering the said chute to its load-discharging position during the further upward movement of the cage.

4. A hoisting cage comprising a frame, a shaft carried thereby, a car support mounted on the said shaft, a chute having one end pivotally secured to the said frame below the said car support, means for holding the said chute raised out of its operative position, and means operable during the upward movement of the cage to lower the said chute to its load-discharging position, and to simultaneously give the said support an initial rotation, thereby displacing the center of gravity of the said support and its load, the said support being thereafter rotated further by gravity, to dump the load.

5. A hoisting cage comprising a car support, a track mounted thereon, two shafts slidably disposed beside the said track, a pair of horns rigidly secured to the said shafts and adapted to grip and hold the front wheels of the car and thereby to stop the movement of the car running on the said support, a buffer spring surrounding each of the said shafts for cushioning the shock of engagement between the said wheels and the said horns, and a second pair of horns also mounted on the said shafts and adapted to grip and hold the rear wheels of the said car.

6. A hoisting cage comprising a car support, tracks carried by the said support, a pair of horns adapted to grip and hold the front wheels of the car and a second pair of horns adapted to grip and hold the rear wheels of the car, means operable during the downward movement of the cage for moving all of the said horns to release the wheels of the car, means operable by the car leaving the said support for bringing the said front horns into operative position, and means operable by the front wheels of the car running upon the support for moving the said rear horns into operative position.

7. A hoisting cage comprising a car support, means for rotating the said support by gravity to dump the car and means auto-

1. A hoisting cage comprising a frame, a car dump rotatably movable by gravity to dump a car, tracks carried by the said dump and a locking member for holding the said dump against rotation for loading, the said locking member being movable parallel with the said tracks.
2. A hoisting cage comprising a frame, a car dump rotatably movable by gravity to dump a car, tracks carried by the said dump and a locking member for holding the said dump against rotation for loading, the said locking member being movable parallel with the said tracks and in the plane thereof.
3. A hoisting cage comprising a frame, a car dump carried by said frame, a chute carried by said frame and movable, independently of said dump, into position to deliver material from the said dump to a stationary receiving hopper, and means for permitting the said chute to rest upon the said hopper if the cage overwinds beyond its normal delivering position.
4. A hoisting cage comprising a frame, a car dump carried by said frame, a chute carried by said frame and movable, independently of said dump, into position to deliver material from the said dump to a stationary receiving hopper, and means for permitting the said chute to rest upon the said hopper if the cage overwinds beyond its normal delivering position.
5. A hoisting cage comprising a frame, a car dump carried by said frame, a chute carried by said frame and movable, independently of said dump, into position to deliver material from the said dump to a stationary receiving hopper, and means for permitting the said chute to rest upon the said hopper if the cage overwinds beyond its normal delivering position.
6. A hoisting cage comprising a frame, a car dump carried by said frame, a chute carried by said frame and movable, independently of said dump, into position to deliver material from the said dump to a stationary receiving hopper, and means for permitting the said chute to rest upon the said hopper if the cage overwinds beyond its normal delivering position.
7. A hoisting cage comprising a frame, a car dump carried by said frame, a chute carried by said frame and movable, independently of said dump, into position to deliver material from the said dump to a stationary receiving hopper, and means for permitting the said chute to rest upon the said hopper if the cage overwinds beyond its normal delivering position.
8. A hoisting cage comprising a car support, means for rotatably moving the said support to dump the car, and means for regulating the speed of rotation of the said support, the said regulating means comprising a fluid-filled cylinder carried by the said support, a fixed shaft, and a fixed crank carried by the said shaft and connected to the piston of the said cylinder.
9. A hoisting cage comprising a frame, a fixed shaft carried by the said frame, a car support mounted on the said shaft, tracks carried on the said support, a set of horns also carried by the said support and adapted to grip and hold the wheels of the car, a fixed crank carried by the said shaft, a fluid-filled cylinder carried by the said support and having its piston connected to the said crank, a chute pivotally attached to the said frame below the said car support, and a member connecting the said car support and the said chute.
10. A hoisting cage comprising a car dump rotatably movable by gravity to dump a car, tracks carried by the said dump and a locking member for holding the said dump against rotation for loading, the said locking member being movable parallel with the said tracks.
11. A hoisting cage comprising a car dump rotatably movable by gravity to dump a car, tracks carried by the said dump and a locking member for holding the said dump against rotation for loading, the said locking member being movable parallel with the said tracks and in the plane thereof.
12. A hoisting cage comprising a car dump rotatably movable by gravity to dump a car, tracks carried by the said dump, and locking means associated with the said tracks for holding the said dump against rotation while receiving a loaded car.
13. A hoisting cage comprising a frame, a car dump carried by said frame, a chute carried by said frame and movable, independently of said dump, into position to deliver material from the said dump to a stationary receiving hopper, and means for closing the end of the cage adjacent to said chute while said dump is moving to dump a car, the said means comprising a plate carried adjacent to the path of movement of the cage and means carried by the cage for engaging the said plate during the upward movement of the cage and for carrying said plate with the cage during its further upward movement.
14. A hoisting cage comprising a rotatable car dump, an operating member adapted to engage a stationary guide disposed adjacent to the path of movement of said cage, and a flexible connection between the said dump and the said operating member.
15. A hoisting cage comprising a car dump, a movable chute adapted to deliver material from the said dump to a stationary receiving hopper, and flexible means for connecting the said chute to the said dump.
16. A hoisting cage comprising a car dump, a pivotally movable chute adapted to deliver material from the said dump to a stationary receiving hopper, and one or more flexible connectors connecting the said chute to the said dump, the said connectors having sufficient slack to permit the said chute to rest upon the said hopper if the cage overwinds beyond its normal delivering position.
17. A hoisting cage comprising a rotatably movable car dump, a chute adapted to receive material from said dump, means for rotating the said dump by gravity to discharge its load, and means associated with said chute for positively returning the said dump toward its upright position.
18. A hoisting cage comprising a rotatably movable car dump, a chute adapted to receive material from said dump, means for rotating the said dump by gravity to discharge its load, and means associated with said chute for positively engaging the said dump and giving it a reverse rotation toward its upright position.
19. A hoisting cage comprising a rotatably movable car dump, a chute adapted to receive material from said dump, means for rotating the said dump by gravity to discharge its load, and means associated with said chute for positively returning the said dump toward its upright position, the dump being adapted to complete its return movement by gravity.
20. A hoisting cage comprising a vertically movable frame, a rotatably movable car dump carried by said frame, means for rotating the said dump by gravity to discharge its load, a delivery chute pivotally carried by the said cage, beneath said dump, means for raising and lowering the said chute while said frame is descending and rising, and means carried by the said chute for engaging and moving the said dump while the said frame is descending from its delivering position and while the said chute is rising, whereby the said dump is given a positive rotation toward its upright position.
21. A hoisting cage comprising a rotatably movable car dump, a chute for receiving material from the said dump, and means for closing the end of the cage adjacent to said chute while said dump is moving to dump a car, the said means comprising a plate carried adjacent to the path of movement of the cage and means carried by the cage for engaging the said plate during the upward movement of the cage and for carrying said plate with the cage during its further upward movement.
22. A hoisting cage comprising a vertically movable frame, a rotatably movable car dump carried by said frame, a chute carried by said frame and adapted to re-

ceive material from said dump, a support mounted adjacent to the path of movement of said frame, near the upper part of its travel, and a plate slidably mounted on said support and adapted to be engaged and lifted by said frame and to close the open end of said frame adjacent to said chute.

In testimony whereof, I, the said VERNOR T. BARKLEY, have hereunto set my hand.

VERNOR T. BARKLEY.

Witnesses:

R. D. BROWN,
JOHN F. WILL.
